UNITED STATES PATENT OFFICE

CARL H. INGWER, OF ELYRIA, OHIO

DESIGN FOR A SHOE HEEL OR SIMILAR ARTICLE

Application filed May 21, 1932. Serial No. 43,864. Term of patent 14 years.

To all whom it may concern:

Be it known that I CARL H. INGWER, a citizen of the United States, residing at Elyria, in the county of Lorain and State of Ohio, have invented a new, original, and ornamental Design for a Shoe Heel or Similar Article, of which the following is the specification, reference being had to the accompanying drawing, forming a part thereof.

The figure is a perspective view of a shoe heel showing my new design.

I claim:

The ornamental design shown for a shoe heel or similar article.

CARL H. INGWER.
